UNITED STATES PATENT OFFICE.

JOHN WILSON BROWN, JR., OF PHILADELPHIA, PENNSYLVANIA.

DESIGN FOR A FRAME OR CASING FOR FOOD-CUTTERS.

SPECIFICATION forming part of Design No. 32,487, dated April 10, 1900.

Application filed March 16, 1899. Serial No. 709,336. Term of patent 14 years.

To all whom it may concern:

Be it known that I, JOHN WILSON BROWN, Jr., a citizen of the United States, residing in Philadelphia, Pennsylvania, have invented 5 and produced a new and original Design for a Frame or Casing for Food-Cutters, of which the following is a specification.

My design for the frame or casing of a food-cutter is clearly illustrated in the accompanying drawings, in which—

Figure 1 is a perspective view of the casing. Fig. 2 is a side view, and Fig. 3 is an end view. The essential features of the design consist 15 of the frame or casing, comprising a small barrel with a perforated tapered front end, a hopper on the top, and a circular enlargement at the rear supported by a round elongated vertical stem, from which projects a foot extension of the shape shown, and a flat rib extending 20 downwardly and terminating in a cylindrical boss directly below said foot extension, said rib having a flange projecting equally on each side thereof at its front and

extending between the cylindrical boss and the said foot extension. 25

B is a standard cylindrical in cross-section, having a horizontal foot extension *b* and a clamp bracket extension *b'* below the foot extension. *b*² is a rib at the back of the standard.

A is a barrel having a circular enlargement 30 *a* connected to the standard, and this barrel is tapered and perforated at the opposite end *a'*, and between the two ends the barrel is ribbed, and projecting upward from the barrel is a hopper *a*². 35

I claim—

The design for the frame or casing of a food-cutter as herein described and as shown in the accompanying drawings.

In testimony whereof I have signed my 40 name to this specification in the presence of two subscribing witnesses.

JOHN WILSON BROWN, JR.
